UNITED STATES PATENT OFFICE.

B. W. BURNET, OF MADISON, NEW JERSEY, ASSIGNOR TO HENRY R. BURNETT, OF MORRISANIA, NEW YORK.

DESIGN FOR ORNAMENTING PAPER COLLARS AND CUFFS.

Specification forming part of Design No. 2,209, dated October 24, 1865.

To all whom it may concern:

Be it known that I, B. W. BURNET, of Madison, in the county of Morris and State of New Jersey, have invented a new and useful ornamental Design for Paper Collars and Cuffs; and I do hereby declare that the same is represented in the accompanying drawings, of which—

Figure 1 represents an elevation of one of my paper collars unfolded with a colored border. Fig. 2 is a similar view of the same when folded with a plain border.

Having thus described my invention, what I claim as new, and desire to secure by Letters Patent, is—

The design for paper collars and cuffs herein described.

B. W. BURNET.
